US00D913613S

(12) **United States Design Patent** (10) **Patent No.:** **US D913,613 S**
(45) **Date of Patent:** **** Mar. 16, 2021**

(54) **WATER TANK FOR DEHUMIDIFYING, DEODORIZING AND WRINKLE-REDUCING MACHINE FOR CLOTHING**

(71) Applicant: **LG Electronics Inc.**, Seoul (KR)

(72) Inventors: **Myungshik Kim**, Seoul (KR); **Donghwan Lee**, Seoul (KR); **Junyi Heo**, Seoul (KR); **Sungkyong Han**, Seoul (KR); **Jeaseok Seong**, Seoul (KR)

(73) Assignee: **LG ELECTRONICS INC.**, Seoul (KR)

(**) Term: **15 Years**

(21) Appl. No.: **35/507,378**

(22) Filed: **Jan. 25, 2019**

(80) **Hague Agreement Data**

Int. Filing Date: **Jan. 25, 2019**

Int. Reg. No.: **DM/202551**

Int. Reg. Date: **Jan. 25, 2019**

Int. Reg. Pub. Date: **Sep. 6, 2019**

(30) **Foreign Application Priority Data**

Jul. 26, 2018 (KR) 30-2018-0034760

(57) **CLAIM**

The ornamental design for a water tank for dehumidifying, deodorizing and wrinkle-reducing machine for clothing, as shown and described.

DESCRIPTION

1. Water tank for dehumidifying, deodorizing and wrinkle-reducing machine for clothing

1.1 : Perspective

1.2 : Front

1.3 : Back

1.4 : Left

1.5 : Top

1.6 : Bottom

1.7 : Perspective shown in use

1.8 : Perspective shown in use environment

1.9 : Detail Perspective shown in use of 1.8

The broken lines depict portions of water tank for dehumidifying, deodorizing and wrinkle-reducing machine for clothing that form no part of the claimed design; the fine lines on the drawings indicate the flat surface, curved surface

(Continued)

or transparent part; and the environment shown in broken lines in 1.7-1.9 forms no part of the claimed design.
